UNITED STATES PATENT OFFICE.

HARRY C. GAMMETER, OF BRATENAHL, OHIO, ASSIGNOR TO THE AMERICAN MULTIGRAPH COMPANY, OF CLEVELAND, OHIO, A CORPORATION OF OHIO.

TYPE-CASE.

1,052,333.

Specification of Letters Patent.

Patented Feb. 4, 1913.

Original application filed March 5, 1907, Serial No. 360,777. Divided and this application filed April 9, 1910. Serial No. 554,356.

To all whom it may concern:

Be it known that I, HARRY C. GAMMETER, a citizen of the United States, residing at Bratenahl, in the county of Cuyahoga and State of Ohio, have invented a certain new and useful Improvement in Type-Cases, of which the following is a full, clear, and exact description, reference being had to the accompanying drawings.

The object of this invention is to provide a simple and efficient type case adapted to hold grooved type and allow their extraction one at a time. The case is primarily designed for use with short type grooved near the middle of its opposite sides, such type being held in the case in rows, all except the endmost type being confined by ribs occupying the type-grooves, such endmost type being so held that it may be conveniently removed by a suitable implement. The type case is preferably arranged so that the type descend by gravity, the bottom-most type resting on a support narrower than the type, whereby a convenient tool having a bifurcated end may straddle such support and engage the grooves in the type and easily effect the removal.

The present invention consists of the means whereby the above features are carried out. Combined with the type case may be suitable mechanism for distributing type into its upper end. Such mechanism is shown, described and claimed in my application #360,777, filed March 5, 1907, of which the present application is a division.

The drawings illustrate my invention embodied in an upright type case for holding short grooved type in banks, one behind the other.

Figure 1 is a perspective view of the type case; Fig. 2 is a perspective view of the type-removing implement, together with a type and that portion of the case which supports the bottom-most type and which is straddled by the removing implement; Fig. 3 is a vertical section of the type case from front to back; and Fig. 4 is a plan of the type case.

As shown in the drawings, 10 represents a suitable standard which carries the type

case proper. The latter has a vertical front plate 11, end plates 12 and 13, and back plate 14, and numerous vertical partitions 15 extending from the front plate to the black plate and having on their sides vertical ribs 16. The ribs of one partition are opposite the ribs of the next, as shown in Fig. 4. The type, indicated by 20, have grooves 21 on their opposite sides, which grooves are adapted to slide over the co-operating ribs of adjacent partitions. Each two ribs, therefore, provide a type repository.

As shown, there are four banks of repositories, one in front of the other, between the front plate and back plate. To illustrate their action in receiving and holding type, four of the type are shown at 20 in Fig. 4. It will be understood that if the type are brought into position over the ribs 70 and are then released, they will fall by gravity into the repositories thus provided.

Fig. 3 shows three of the repositories containing type and one empty. The bottom type of the pile in each repository rests on a block 23 at the base of the repository carried by a cross bar 24. Each of the four banks of repositories terminates some distance above the bank at the rear thereof, as shown in Figs. 1 and 3, the bottom edge of 80 each plate 24 being higher than the lower edge of the repository next as the rear thereof. The bottom type in every repository is therefore accessible from the front of the case. The ribs 16 terminate a short 85 distance above the blocks 23, this distance being somewhat greater than the thickness of one type and less than the thickness of two types, while the partition walls extend slightly below the upper edges of the bottom type. The bottom type is therefore free from the ribs and may be moved forward on the block 23, but cannot fall off sideways. The cross bar 24, which carries the supporting blocks 23 at the ends thereof corresponding to the foot of the type, rises above those blocks and is hollowed or recessed on its forward face, as shown at 25, so that it stands on the rear side of the bottom type and prevents rearward move- 100

ment thereof. The blocks 23 have a width about equal to that of the shank of the type between the two grooves 21 and project freely from the cross bar 24 in the direction of the length of the type—that is to say, the blocks have their sides out of contact with any parts of the mechanism, whereby they are adapted to be straddled by a suitable bifurcated member, or a pair 10 of adjacent prongs, which may thus enter the grooves of the lowermost type and draw it forwardly off of the block.

In Fig. 2 is shown a bifurcated and pronged member, for use in removing the 15 type as above referred to, consisting of a tube 30 having a longitudinal slit 31 of width slightly greater than the shank of the type. The tube is preferably curved at one end and the rear portion thereof is 20 cut off diagonally at this curved portion so that two prongs 32 are provided. These prongs may be passed upwardly on opposite sides of the block 23 into the grooves 21 of the type. Then a slight forward 25 movement of the tube draws the type forward off of the block 23, allowing it to drop by gravity into the grasp of the tube 30. The type gradually pass around the curve of this tube as one after the other are picked 30 out of the various cases, and a swinging of the tube into an upwardly-inclined position allows the type to slide down the groove 31 until they are stopped by coming against an abutment, which may be provided by a 35 spring clip 34 sprung around the tube near its other end, as shown in Fig. 2. The blocks 23 are preferably tapered at their lower edges to allow the easy placing of the tube fork about them. On the face of 40 the plates 24 directly below the blocks are suitable characters, as shown in Fig. 1, to indicate the characters contained in the case.

With this mechanism, an operator may 45 assemble type on the tubular holder with great rapidity. He simply moves the tube around by hand and lifts its prongs upward, straddling the blocks and passing into the grooves of the type, when a slight forward movement releases the type to pass 50 down the tube. As soon as any type is released, the type remaining in the repository above it descends, so that the bottom type rests on the block ready for the next removal. After the line is assembled along 55 the tube it may be transferred by hand to any suitable printing mechanism, the clip 34 being removed to allow it to pass out of the straight end of the tube.

As heretofore stated, the parent application of which this is a division, shows, describes and claims suitable mechanism for 60 distributing type into the type case at its upper end. Such mechanism may be em-

ployed, if desired, or the type may be distributed by other mechanism, or without any mechanism, simply being dropped by hand into the respective repositories. On the face of the type case near its upper end will be seen four rows of characters. Each of these rows corresponds to one of the 70 banks of the cases. By means of these characters the operator may tell into which repository to drop the type.

Having thus described my invention, what I claim is:

75

1. In a type case, a series of vertical plates having each a plurality of ribs one behind the other, certain of the ribs extending lower than ribs in front thereof.

2. In a type case, in combination, a supporting base, vertical walls carried thereby, parallel vertical partitions between the walls, parallel vertical ribs on opposite sides of each partition, ribs on adjacent portions facing each other, and means for supporting the type located below the ribs a distance slightly greater than the thickness of the type.

3. In a type case, in combination, a supporting base, vertical walls carried thereby, parallel vertical partitions between the walls, parallel vertical ribs on opposite sides of each partition, ribs on adjacent partitions facing each other, each cross row of ribs extending at its lower end below the row in front thereof to allow convenient exit from the several holders.

4. The combination of a type case comprising holders arranged in banks one in front of the other, each holder having on the side a rib adapted to enter a groove in the side of the type, the different banks terminating at their lower ends higher than the banks at the rear thereof, and blocks narrower than the widest portion of the type and projecting in the direction of the length of the type located below the holders at a distance below the ribs slightly greater than the thickness of a type.

5. The combination of a type case comprising holders arranged in banks one in front of the other, each holder having a rib adapted to enter a groove in the side of the type, the different banks terminating at their lower ends higher than the banks at the rear thereof, blocks located a distance below the ribs slightly greater than the thickness of a type, and a plate secured along the front side of each bank near its lower end and carrying the blocks for the bank in front thereof.

6. The combination, in a type case adapted to contain type grooved on its opposite sides, holders arranged in banks one in front of the other, each holder having ribs adapted to enter the groove in the sides of

110

115

125

- the type, the different banks terminating at their lower ends higher than the banks at the rear thereof, and blocks narrower than the type and located a distance below 5 the ribs slightly greater than the thickness of a type, whereby a member adapted to receive the type from the various cases may straddle the blocks and enter the grooves in the type.
10. 7. A type case having vertical walls and vertical partitions, said partitions extending from one wall to the opposite wall, and ribs on the opposite sides of the partitions whereby a plurality of the banks of type holders 15 are provided, each bank being arranged to have its lower end terminate above the lower end of the banks at the rear thereof.
8. A type case having vertical walls and vertical partitions, said partitions extending 20 from front to back, ribs on opposite sides of the partitions whereby a plurality of the banks of type holders are provided, each bank being arranged to have its lower end terminate above the lower end of the banks 25 at the rear thereof, and means for supporting the bottom-most type in each holder with its grooves freed from the ribs of the holder.
9. In a type case, the combination of a plurality of banks arranged one behind the 30 other, the rear bank or banks extending below any bank in front thereof and each bank comprising a series of channels side-by-side, a cross member common to the various channels of the bank, and individual supports 35 for the type carried by such cross member and projecting therefrom in the direction of the length of the type each support being narrower than the widest portion of the type whereby a suitable tool may straddle the 40 support and engage the type.
10. In a type case, the combination of a plurality of banks arranged one-behind the other, the rear bank or banks extending below any bank in front thereof and each bank 45 comprising a series of channels side-by-side and adapted to hold type facing forwardly, a cross member adjacent to the lower end of the various channels in the bank, and a series of separated projections on the forward 50 side of the cross member narrower than the type and projecting forwardly and adapted to individually support type in the corresponding channel.
11. In a type case, the combination of a 55 plurality of banks arranged one behind the other, the rear bank or banks extending below any bank in front thereof and each bank comprising a series of channels side-by-side and adapted to hold type facing 60 forwardly, a cross member adjacent to the lower end of the various channels in the bank, a series of separated projections on the forward side of the cross member adapt-
- ed to individually support type in the corresponding channel, said channels being 65 provided with ribs adapted to enter grooves in the opposite sides of type, such ribbed portions of the channels terminating a distance above the projections at least as great as the thickness of a type, and means for 70 confining the bottom type laterally when it is on the support while leaving it free to move forwardly on the support.
12. In a type case, the combination of banks arranged one behind the other, the 75 rear banks extending below those in front thereof, and each bank comprising a series of type channels side-by-side and a series of individual supports for the type narrower than the widest portion of the type 80 and projecting lengthwise of the type and free at the sides and front, said supports being located side-by-side and in position to receive the lowermost type of the corresponding channel above the exit of channels in any of the banks at the rear thereof. 85
13. The combination of a series of ribbed members side-by-side providing type channels, a cross bar near the lower ends of the channels and adapted to extend on to the 90 rear side of the bottom type therein, individual projections carried on the forward side of the cross bar below the corresponding channels, the ribbed portion of the members terminating a distance above the projections and side portions of the members continuing below the termination of their 95 ribbed portions to laterally guide the bottom type.
14. A type holder having a pair of parallel 100 separated guiding members adapted to occupy grooves in the opposite sides of a row of type, and an abutment in alinement with the space between such members and of a width narrower than the widest portion of the type held by said members, the guiding members terminating a distance above the abutment greater than the thickness of one type and less than the combined thickness of two type. 105
15. A type holder having a pair of parallel 110 separated guiding members adapted to occupy grooves in the opposite sides of a row of type, and an abutment in alinement with the space between such members, the width of the abutment being substantially equal to that of the space between the guiding members, the guiding members terminating a distance above the abutment greater than the thickness of one type and less than the combined thickness of two type. 115
16. In a type case, a series of parallel 120 partitions extending in the direction from front to back and stepped backwardly and downwardly near their lower ends, plates 125 extending crosswise of the partitions and

secured to the edges of the partitions at such steps and type supporting blocks carried by such cross plates.

17. In a type case, a series of parallel partitions stepped near their lower ends, plates extending crosswise of the partitions at such steps, type supporting blocks carried by said cross plates, and ribs on the partitions rising from points a short distance above the blocks.

18. The combination, with means for guiding laterally grooved type in a column, the type being adapted to descend by gravity, of a support for the bottom type narrower than the type, said means being adapted to enter the grooves of the type but being recessed above the support for a distance greater than the thickness of a type and less than the combined thickness of two type, thereby confining all but the bottom type, the bottom type being free when on the support, and the support being carried at an end corresponding to the foot of the type and free at its sides.

19. The combination, with means providing a channel adapted to hold type grooved on its opposite sides and having ribs occupying such grooves, of a support for the type narrower than the width of a type and located a distance below the lower ends of said ribs greater than the thickness of a type and less than the thickness of two types.

20. A type holder having a pair of parallel separated guiding members adapted to occupy grooves in the opposite sides of a row of type, and an abutment in alignment with the space between such members and of a width narrower than the widest portion of the type held by said members, the face of the abutment on the opposite side from such space being tapered, the guiding members terminating a distance above the abutment greater than the thickness of one type and less than the combined thickness of two type.

21. The combination of a series of ribbed members side-by-side providing type channels, a cross bar, individual projections thereon below the corresponding channels, the ribbed portion of the members terminating a distance above the projections greater than the thickness of one type and less than that of two type and the members continuing below the termination of their ribbed portions.

22. In a type case, a series of type holders arranged side-by-side and having parallel facing ribs adapted to occupy the grooves of type grooved on its opposite sides, and individual supports for the type located below the holders and narrower than the type, the ribs being omitted above the supports for a

distance at least as great as the thickness of a type and less than the thickness of two type.

23. In a type case, a series of typeholders arranged side-by-side and having parallel facing ribs adapted to occupy the grooves of type grooved on its opposite sides and hold such type in columns facing forwardly, and individual supports for the type located below the holders and narrower than the type, the ribs being omitted above the supports for a distance at least as great as the thickness of a type and less than the thickness of two type but the side walls of the holders continuing nearer to the supports, and a bar extending crosswise of the various holders and carrying such individual supports on its forward side.

24. In a type case, a series of type channels, and a series of abutments in alignment with the respective channels to prevent discharge of the type in the direction of the length of the channels, there being a discharge recess between the abutments and the ends of the channels of such dimensions as to permit a type to be withdrawn singly when in contact with the abutment, said abutments being narrower than the extreme width of the type, whereby the abutment may be straddled by a composing stick having a bifurcated end.

25. In a type case, the combination of a type holder adapted to confine type grooved on its opposite sides, an abutment opposite the end of the holder to prevent discharge of the type in the direction of the length of the holder, there being a discharge recess from the holder adjacent to the abutment, said abutment being tapered at the edge opposite the type to enable it to be conveniently straddled by a bifurcated composing tool.

26. In a type case, the combination of parallel ribs adapted to enter grooves of type grooved on its opposite sides, said ribs being so positioned that the type may descend by gravity thereon, an abutment in alignment with the channel defined by the ribs, which abutment is not much wider than the shank of the type between the grooves, whereby a bifurcated member may straddle the abutment and enter the grooves, the ribs referred to being omitted or cut away for a distance above the abutment somewhat greater than the thickness of a type but less than the thickness of two types, whereby the bottom type only is freed and may be drawn forwardly off of said abutment, there being a provision made for confining the bottom type against lateral displacement when on the abutment.

27. The combination, with means for holding grooved type in rows, said means including ribs occupying the grooves of all the

type except the endmost, individual stops in the line of said rows narrower than the type, and means for confining the endmost type at its foot while it is free from the ribs and engages the stop.

28. A typeholder device having a slot, and a tapered abutment at the end of said slot in alignment therewith and of no greater width than the slot, the typeholder having

a recess adjoining said abutment of greater width than said slot.

In testimony whereof, I hereunto affix my signature in the presence of two witnesses.

HARRY C. GAMMETER.
